UNITED STATES PATENT OFFICE.

GEORGE ALFRED RATHBUN, OF COALINGA, CALIFORNIA.

GLASS PUMP.

1,184,018.

Specification of Letters Patent.

Patented May 23, 1916.

Application filed August 22, 1914. Serial No. 858,105.

To all whom it may concern:

Be it known that I, GEORGE ALFRED RATHBUN, a citizen of the United States, residing at Coalinga, in the county of Fresno and State of California, have invented a new and useful Glass Pump, of which the following is a specification.

The device forming the subject matter of this application is a pump adapted to be employed upon Artesian and oil wells.

One object of the present invention is to provide a pump of the type described in which the liner of the barrel and the jacket of the piston or plunger are fashioned from glass.

Another object of the invention is to provide a pump embodying a construction which will make possible the use of glass in the formation of the elements above mentioned.

Another object of the invention is to provide a pump embodying means whereby an increment of the material handled by the pump may be permitted to enter between the casing and the liner of the pump barrel, thereby to form a sustaining cushion.

It is within the scope of the invention to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings:—Figure 1 shows in vertical longitudinal section, a pump embodying the present invention; Fig. 2 is a cross section on the line 2—2 of Fig. 1; Fig. 3 is a cross section on the line 3—3 of Fig. 1; Fig. 4 is a fragmental longitudinal sectional detail enlarged from Fig. 1; Fig. 5 is a cross section on the line 5—5 of Fig. 1.

The barrel of the pump herein disclosed comprises a casing 1 which preferably is made of metal. The casing 1 of the pump barrel is of tubular construction and located in the casing is a tubular liner 2 which preferably is made of glass. The liner 2 is

spaced from the casing 1, as indicated at 11. Threaded or otherwise secured to the lower end of the casing 1 is a cap 3, comprising an upstanding flange 4 to which the casing 1 is immediately secured. The cap 3 includes a depending flange 5. The cap is centrally open as indicated at 6. The lower end of the liner 2 abuts against the cap 3 and thus the cap 3 forms a closure for the lower end of the space 11 existing between the casing and the liner. An upper cap 7 is provided, the cap 7 being equipped intermediate its ends with an inwardly extended flange 8 against which the upper end of the liner 2 abuts, the cap being shouldered as indicated at 9 to receive the upper end of the casing 1. The cap 7 embodies a depending flange 12 to which the casing 1 is threaded, the cap including an upstanding flange 14 having a threaded connection with the tubing 15 of the well. In the transverse flange 8 of the cap 7 are formed a plurality of notches 10. These notches 10 give access to the space 11 between the casing 1 and the liner 2 so that, when the piston of the pump is in operation, oil, sand, or other material handled by the pump may find its way between the casing 1 and the liner 2 to serve as a cushion between these elements. The material thus located is indicated by the reference character 32.

The novelty in the present invention resides essentially in the pump barrel and in the piston and it will therefore be understood that any form of foot-valve may be employed. In the present instance, and by way of illustration, a tube 16 is threaded into the flange 5 of the lower cap 3 and threaded to the lower end of the tube 16 is a foot 17 into which is threaded a cage 18 carrying a ball valve 19. Fixed to and upstanding from the cage 18 is a rod 20. However, as hereinbefore stated, any form of foot-valve may be employed.

The plunger or piston of the pump is a composite structure and embodies a tubular core 21, preferably fashioned from metal. Surrounding the core 21 is a tubular jacket 22 embracing the core closely and preferably made of glass. A washer 23, ordinarily made of metal, surrounds the lower portion of the tubular core 21 and forms an abutment for the lower end of the jacket 22. A nut 24 is threaded onto the lower end of the core 21 and holds the washer 23 in place, the

nut 24 having an opening 25 through which the rod 20 passes, the opening 25 being of considerably greater diameter than the rod 20, in order to permit the material which 5 is operated upon to pass readily through the plunger or piston when the latter is reciprocated. The upper end 26 of the core 21 of the piston upstands above the upper end of the jacket 22. Threaded onto the end 10 portion 26 of the core 21 is a nut 27 having a transverse shoulder 28 which engages the upper end of the core 21. Threaded or otherwise secured to the exterior of the nut 27 is a cage 29 containing a ball valve 30 co- 15 operating with a valve seat 50 bound between the nut and the cage.

The numeral 31 indicates any suitable means for imparting a reciprocating motion to the plunger or piston.

20 So far as the general operation of the pump herein disclosed is concerned, it will be understood that when the piston moves downwardly, the valve 19 will close and the valve 30 will open, and, when the piston 25 moves upwardly, the valve 30 will close and the valve 19 will open. The function of the rod 20 is to unseat the valve 30 at the extremity of the downward stroke of the piston, should the valve 30 be stuck in its seat.

30 As outlined hereinbefore, an increment of the material handled by the pump passes through the notches 10 in the cap 7 and enters between the casing 1 and the liner 2 to form a cushion, as shown at 32.

35 In the pump herein disclosed, glass works upon glass as the piston or plunger reciprocates. The jacket 22 of the piston and the liner 2 of the pump barrel, being made of glass, will not score or wear rapidly, under 40 the attrition of the material which is handled. The general construction is such that

glass may be used to fashion certain elements hereinbefore referred to specifically.

The washer 23 prevents a cracking or chipping of the glass jacket 22 by the nut 24. 45

Having thus described the invention, what is claimed is:—

1. In a pump, a barrel; and a piston mounted to reciprocate in the barrel; the piston comprising a tubular core; nuts 50 threaded on the ends of the core; a jacket surrounding the core and located between the nuts; and a spacer surrounding the core and located between one nut and the end of the jacket. 55

2. In a pump, a barrel; and a piston mounted to reciprocate in the barrel, the piston comprising a tubular core; nuts mounted on opposite ends of the core; a tubular jacket surrounding the core and located between the nuts; a ball cage threaded onto one nut; and a ball in the cage, the ball coöperating with said nut. 60

3. In a pump, a barrel comprising a casing; a glass liner in the casing and spaced from the casing to define an open compartment; a cap forming a connection between the end of the casing and the liner, the cap having an opening communicating with the compartment, and constituting a means 65 whereby the piston lifted liquid may be deposited in to the compartment to act as a cushion for the liner; and a piston mounted to reciprocate in the liner. 70

In testimony that I claim the foregoing as 75 my own, I have hereto affixed my signature in the presence of two witnesses.

GEORGE ALFRED RATHBUN.
